DESIGN FOR A PERFUME BOTTLE OR SIMILAR CONTAINER

James L. Younghusband, Chicago, Ill.

Application November 9, 1937, Serial No. 72,724

Term of patent 14 years

To all whom it may concern:

Be it known that I, James L. Younghusband, a citizen of the Dominion of Canada, residing at 11 Hubbard Street, Chicago, Illinois, have invented a new, original, and ornamental Design for a Perfume Bottle or Similar Container, of which the following is a specification, reference being had to the accompanying drawing, forming a part thereof.

Fig. 1 is a perspective view of my perfume bottle or similar container in closed position and Fig. 2 in open position.

The dominant feature of my design resides in the lower or bottle portion of my perfume container with its centrally positioned upstanding neck and rounded stopper as shown in Fig. 2.

I claim:

The ornamental design for a perfume bottle or similar container, substantially as shown and described.

JAMES L. YOUNGHUSBAND.
